FRANCIS J. DROBINSKI, OF NEW YORK, N. Y., ASSIGNOR TO REVERE RUBBER COMPANY, OF CHELSEA, MASSACHUSETTS, A CORPORATION OF RHODE ISLAND.

VENTILATING-CUSHION FOR FOOTWEAR.

1,029,110.

Specification of Letters Patent. Patented June 11, 1912.

Application filed March 31, 1911. Serial No. 618,071.

To all whom it may concern:

Be it known that I, FRANCIS J. DROBINSKI, a citizen of the United States, residing in the borough of Brooklyn, county of Kings, 5 city and State of New York, have invented certain new and useful Improvements in Ventilating-Cushions for Footwear, of which the following is a specification.

My invention relates to a cushion adapted 10 for insertion within a boot or shoe or other article of foot-wear, and has for its object to produce a cushion which will be elastic and resilient, and will therefore provide against a transmission of shocks in walking, 15 etc.

A further object of my invention is to produce a cushion which will have the effect of ventilating the article of foot-wear to which it is applied.

20 A desirable mode of carrying my invention into effect is illustrated in the accompanying drawings, wherein,—

Figure 1 is a longitudinal section of a portion of a shoe having one form of my invention in place; the section line of the cushion being on the line 1—1 of Fig. 3; Fig. 2 is a perspective view of a cushion in which my invention is embodied; Fig. 3 is a horizontal section of the device shown in 30 Fig. 2; Fig. 4 is a detail front view of the cushion illustrated in Fig. 1; and Fig. 5 is a cross-section on the line 5—5 in Fig. 3.

The particular embodiment of invention 35 illustrated is a heel cushion wherein the air passages are situated at the front of the cushion. The invention is of course equally applicable to cushions which will cover the entire bottom of the shoe, and which will embody the same construction illustrated in 40 the drawing, and therefore to avoid duplication I have illustrated such cushion separately. The air passages may be variously disposed to suit the particular size or shape of the cushion.

45 My invention as illustrated employs two plates, an upper plate A and a lower plate B, which are connected by a series of hollow columns C. Preferably the entire structure is composed of some elastic and resilient material, for which purpose soft vulcanized rubber is well adapted, and in such case the columns C will be formed of the same material and will be vulcanized to the upper 50 and lower plates. The form of such columns

permits them to remain in extended position 55 and to maintain the plates separated, as illustrated in Fig. 1, while at the same time they readily yield under pressure and collapse without injury. In this particular the hollow columnar supports are a great improvement upon the solid support, which does not collapse so readily and is apt to break. The said plates are closed about their edges by a front wall D and a side wall E, which closes both sides and the 60 back of the device.

The front wall of the cushion is provided with passages d which lead from the exterior into the interior of said cushion, and by reason of the fact that the structure comprises a collapsible box, the only openings to which are the said passages, a bellows is thereby produced which alternately forces air through the said passages d into the shoe and withdraws the air from the shoe into 75 the receptacle or cushion. A highly desirable circulation of air within the shoe and ventilation thereof is thereby attained.

The longitudinal section, Fig. 1, shows that the device is slightly convex longitudinally upon its upper surface, and tapers from front to rear, the least thickness being at its forward end, and this in combination with a certain amount of convexity upon the upper surface transversely as illustrated 85 in Fig. 5, I have found furnishes a desirable shape, but I do not regard the same as essential.

90 My invention may well be made of suitable resilient and elastic material, and this is particularly true of the hollow columns C, which should be collapsible, and should also tend to restore themselves to their original upright position. The said hollow columns C should therefore be connected 95 by an air-tight connection to the upper and lower plates. The same degree of flexibility in the upper and lower plates as in the columns is not essential, but by reason of the fact that a more desirable connection between the columns and the plates, and also the side walls and the front, may be had if all of the said parts are formed of rubber and vulcanized together, I prefer to make the entire device of soft vulcanized rubber. 100 Therefore should the said device be entirely made of soft vulcanized rubber to overcome 105 any objections which might arise from the

influence of the rubber upon the foot of the wearer, I may provide a leather insole F.

My invention is not necessarily limited to the precise form, shape or relative arrangement of parts illustrated, but is subject to variations and modifications thereof within the limits of the appended claims.

I claim as my invention:—

- 10 1. A cushion for shoes comprising upper and lower plates each formed of an integral piece of soft rubber, and hollow columns located perpendicularly to said plates and each connected to both of said plates, said 15 columns formed of soft rubber and said plates serving to close said columns and form independent air cells in each column and to maintain said columns in position.
- 20 2. A cushion for shoes comprising upper and lower plates, a vertical wall connecting said plates at their edges, and hollow columns formed of elastic and resilient material and connected to both said plates, whereby said columns form air cells adapted 25 to return said plates to position after compression, and are maintained in place by said plates, the whole constructed of soft rubber and said top and bottom plates and vertical wall connected by an air tight connection and forming a bellows-like structure and said structure provided with an opening 30 for the passage of air.
- 35 3. A cushion for shoes comprising upper and lower plates closed at their edges, and hollow columns each connected to both of said plates, the whole formed of soft rubber,

and said structure provided with an opening for the passage of air, and forming a bellows-like cushion.

4. A cushion for shoes comprising upper 40 and lower plates, hollow columns each connected to both of said plates and walls connected to said plates, the whole formed of soft rubber vulcanized together and one of said walls being provided with an air passage 45 forming a bellows-like cushion.

5. A cushion for shoes comprising upper and lower plates, hollow columns each connected to both of said plates and walls connected to said plates forming an inclosure, 50 the whole formed of soft rubber vulcanized together and the front wall of said structure being provided with an air passage.

6. In a cushion heel, top and bottom plates connected at their edges forming an air 55 chamber between them, posts interposed between said plates and connected to one of said plates, adapted to restore said plates to separated condition after compression, said posts and the plate to which they are 60 connected being formed of soft rubber vulcanized together, and the said structure being provided with an opening at its front end and forming a bellows-like cushion.

In witness whereof, I have hereunto 65 signed my name in the presence of two subscribing witnesses.

FRANCIS J. DROBINSKI.
